UNITED STATES PATENT OFFICE.

GUSTAVE O. DEGENER, OF HARTFORD, CONNECTICUT, ASSIGNOR TO ROYAL TYPEWRITER COMPANY, INC., OF NEW YORK, N. Y., A CORPORATION OF NEW YORK.

TYPEWRITING MACHINE.

Application filed July 14, 1924. Serial No. 726,019.

To all whom it may concern:

Be it known that I, GUSTAVE O. DEGENER, a citizen of the United States, residing at Hartford, in the county of Hartford and State of Connecticut, have invented certain new and useful Improvements in Typewriting Machines, of which the following is a specification.

This invention relates to the paper feeding and guiding mechanism of typewriting machines. In the Royal Standard machine the paper is fed around the platen by a group of feed rolls which can be released when it is desired to insert or adjust paper upon the platen. There have also been provided combined pressure and feeding rolls which normally hold the paper against the top of the platen after it has passed the printing point. These upper pressure rolls 20 may be moved from their normal or working position on top of the platen to a position in the rear of the platen.

It has also been proposed to provide upper rolls which are not only capable of such movement to the rear of the platen, but also have an independent movement from their position in contact with the platen to a position a considerable distance in front of the platen so that there is a clear space between these pressure rolls and the platen sufficient to permit the paper passing around the platen to pass upwardly between the rolls and the platen without any manipulation thereof. When the forwardly movable rolls 30 are then returned to working position they will press the paper against the platen above the printing point.

The present invention is an improvement on preceding constructions and provides a bail carrying the pressure rolls which has side pieces that are pivoted to the usual forwardly extending side arms at points above the plane of the pressure rolls. These pressure rolls are held against the platen by the usual springs which hold the side arms in position, and when it is desired to move the pressure rolls to inoperative position, the side arms are lifted slightly and the roll carrying bail will swing downward and forward by the force of gravity to a position where paper fed up around the front of the platen will pass between the platen and the pressure rolls without any manipulation.

Further objects of the invention will be

apparent from the following detailed description and the appended claims.

In the drawings:

Figure 1 is a side elevation of portions of a typewriting machine taken from the right side thereof and disclosing the invention 60 with the pressure rolls in operative position.

Figure 2 is a similar view with the pressure rolls in inoperative position.

Figure 3 is a top plan view with the pressure rolls shown in operative position in 65 full lines and in inoperative position in dotted lines.

Figure 4 is a side elevation of a modification.

Figure 5 is a side elevation of another 70 modification.

The drawings illustrate portions of a typewriting machine sufficient to disclose the invention.

The invention comprises a shift rail or frame A, carriage side plates B, a platen C mounted therein, the paper apron D, the usual rearwardly swinging paper table E pivoted at e to the side plates of the carriage and held in position by a spring e', all of which parts are illustrated as being of the construction usually employed in the Royal Standard machine, but which, so far as the invention is concerned, may be of any desired type. There is also shown the bar F connecting the side plates B of the carriage and the margin stop bar G.

There is also illustrated the usual overhead bail frame comprising side arms L, L', joined together by a transverse rod M and pivoted to the carriage side plates at l. This frame may occupy the position shown in Figures 1 and 2, or may be swung to the rear of the paper table as indicated in dotted lines in Figure 2 which show merely a portion of the side arm L. Springs N, connected at one end to the carriage side plates B and at the other end to the side arms L, L' are so positioned with relation to the pivots l of the bail frame that they hold it in either operative or inoperative position. This structure also is similar to that shown in the Royal Standard machine.

However, instead of mounting the roll carrying rod directly in the ends of the side arms L, L' as in the preceding structure, it is carried by side plates O, pivoted at o to the side arms L, L' and supporting near

their free ends the rod P upon which are longitudinally and rotatably mounted a plurality of pressure rolls S. The pivot points o are at the upper front corners of the plates 5 O, and when in operative position these plates extend rearwardly substantially parallel with the arms L, L'. The upper rear portion of each plate is provided with a bent lip R, which underlies its associated 10 arm L or L', and the rolls S are pressed against the platen C by the springs N which exert a downward pull on these arms. One or both of the arms L, L' is provided with a downward extension T between which and 15 the side frames B of the carriage there is normally a clearance x which permits the springs N to exert the desired pressure upon the pressure rolls.

When it is desired to release the pressure 20 rolls, the side arms L, L' are lifted slightly and the roll carrying bail swings about the pivots o under the force of gravity to the position shown in Figure 2. It may be noted that when the bail is moved to the 25 inoperative position of Figure 2 the extensions T come in contact with the side frames of the carriage and prevent excessive downward movement. The length of the arms L, L' and plates O are so proportioned that 30 when the roll carrying bail is in this inoperative position paper may pass around the front of the platen and upwardly between the rolls S and the platen without any manipulation.

35 Each plate O is provided with a finger piece W and when it is desired to move the bail from the Figure 2 position to that of Figure 1, it is swung by one or both of these finger pieces, the frame L, L' being 40 slightly lifted.

In the modification shown in Figure 4, all parts are as above described except that there is provided a spring V which normally holds the swinging bail with the lips 45 R in engagement with the side arms L of the frame. The bail can at any time be moved to inoperative position by means of the finger pieces W.

In the modification shown in Figure 5 50 all parts are as above described, except there is provided a spring V' which normally holds the swinging bail in inoperative position with the lips R' in engagement with the stops on the side of the arm L' of the 55 frame. The bail can, at any time, be moved to operative position by means of the finger piece W'.

There is provided by this invention a 60 swinging auxiliary roll carrying bail pivoted in the front end of the side arms of the main bail or frame but at points above the plane of the rolls. The rolls are held against the platen by the springs which

govern the position of the main bail. A 65 minimum of parts is therefore obtained and the device is simple to manufacture and use although fully efficient. Obviously detail changes may be made without in any manner departing from the spirit of the invention which is to be regarded as limited 70 only by the scope of the appended claims. I claim as my invention.

1. In a typewriting machine, the combination of a platen carriage, a movable frame mounted therein to move rearwardly 75 from operative position, and a roll carrying bail connected to said frame above the plane of the rolls and movable to a position in front of the platen.

2. In a typewriting machine, the combination of a platen carriage, a movable frame mounted therein to move rearwardly from operative position, and a roll carrying bail pivotally connected to the front ends 85 of said frame above the plane of the rolls 85 and swinging to a position a considerable distance in front of the platen.

3. In a typewriting machine, the combination of a platen carriage, a rearwardly movable frame comprising side arms mounted therein, and a roll carrying bail comprising side plates pivoted near their upper front corners to the front ends of 90 said side arms and swinging to a position a considerable distance in front of the 95 platen.

4. In a typewriting machine, the combination of a platen carriage, a rearwardly movable frame mounted therein, springs for holding it in operative position, and a 100 roll carrying bail comprising side plates pivotally mounted near the front ends of said frame and pressed against the platen by said springs, said bail swinging when released from said platen to a position considerably in front of the same. 105

5. In a typewriting machine, the combination of a platen carriage, a rearwardly movable frame mounted therein, plates hinged at their upper sides to the front 110 ends of the frame, a roll carrying rod mounted in the lower rear portion of said plates, and rolls carried by said rod and when in operative position bearing upon the top of the platen, the rod and plates swinging to a position in front of the platen when 115 released from engagement therein.

6. In a typewriting machine, the combination of a platen carriage, a rock shaft frame comprising side arms pivoted to said carriage and a roll carrying bail depending from the side arms of the rock shaft frame. 120

In testimony whereof, I have hereunto subscribed my name.

GUSTAVE O. DEGENER.
